Primary Examiner — Janice Hallmark*Assistant Examiner* — Harold E Blackwell, II(74) *Attorney, Agent, or Firm* — Dinsmore & Shohl, LLP(57) **CLAIM**

The ornamental design for an equipment mounting plate, as shown and described.

DESCRIPTION

FIG. 1 is a top perspective view of an equipment mounting plate illustrating our new design;

FIG. 2 is a top view thereof;

FIG. 3 is a bottom view thereof;

FIG. 4 is a side view and the opposite side being the same; and,

FIG. 5 is an enlarged detail front view and the back view being the same.

The dash-dash broken lines, where present, in the figures depict portions of the equipment mounting plate that represent the environment of the claimed design and form no part of the claimed design. The dash-dot-dash boundary lines, where present, in the figures depict boundaries of the equipment mounting plate and form no part of the claimed design.

1 Claim, 5 Drawing Sheets# US D868,569 S
